(57) **CLAIM**

The ornamental design for a curtain cover, as shown and described.

DESCRIPTION

FIG. 1 is a perspective view of a curtain cover, showing our new design;

FIG. 2 is another perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof;

FIG. 8 is a bottom plan view thereof;

FIG. 9 is an enlarged portion view taken from an encircled portion labeled "9" in FIG. 4; and,

FIG. 10 is an enlarged view of FIG. 5.

The evenly broken lines where present illustrate portions of the curtain cover that form no part of the claimed design. The dashed-dot lines in FIG. 4 and FIG. 9 are for the purpose of depicting the boundary lines of the enlarged views and form no part of the claimed design.
